UNITED STATES PATENT OFFICE.

CARYL D. HASKINS, OF LYNN, MASSACHUSETTS, ASSIGNOR TO THE GENERAL ELECTRIC COMPANY, OF NEW YORK.

ELECTRIC SNAP-SWITCH.

SPECIFICATION forming part of Letters Patent No. 501,068, dated July 11, 1893.

Application filed January 24, 1893. Serial No. 459,543. (No model.)

To all whom it may concern:

Be it known that I, CARYL D. HASKINS, a citizen of the United States, residing at Lynn, in the county of Essex, State of Massachusetts, have invented certain new and useful Improvements in Electric Snap-Switches, of which the following is a specification.

My invention relates to switches, and more particularly to snap switches, so called, for electric light circuits, wherein it is of importance to break contact quickly and completely in order to avoid the formation of arcs and the consequent destruction of the contacts; and has for its object to provide such a switch with a simple and effective spring having considerable range of action, and also to provide means whereby the switch may be thrown into action by a push button located at any convenient place.

20 To this end I provide a spring consisting of a single piece of spring wire coiled in a peculiar manner, to be more particularly described hereinafter. I also arrange the switch so that its handle may be held under tension by means 25 of a trigger connected to the armature of an electro-magnet, which I place in circuit with a battery, leading in the wires through a suitable push button; so that, when the circuit is complete, the armature is attracted, the trigger released, and the spring throws the switch to its second position.

In the drawings annexed to and forming part of this specification, in which like letters refer to like parts, and which show one mode 35 of embodying my invention, Figure 1 is a plan and Fig. 2 a sectional elevation of a switch made according thereto.

Referring by letter, A is a base upon which the switch is constructed, properly mounted 40 upon standards or supports B B, or in any other manner.

C C, &c., are contact points to join which the switch is constructed, D D being arms or plates of the switch, which is of the ordinary 45 jackknife construction. As shown in the drawings the switch is in its first position, thus placing the spring F under tension, and being held in such position by the trigger H engaging the lug I upon the switch handle; 50 the trigger being maintained in position to engage the lug by the spring J. To the back

of the trigger is fixed the armature O of the electro-magnet G G. This electro-magnet is in circuit with the battery L by means of wires K K and push button M.

As seen in the drawings the spring F is made of a single piece of hard drawn brass wire secured to the base plate by means of a plate a and suitable bolts or screws; to increase its power it is coiled several times into 60 the close helices f f and its middle portion is carried up under a pin N which secures it to the handle E of the switch. The action of this arrangement is apparent from the preceding description and is briefly thus: The 65 switch is normally set to the position shown in the drawings, and when the engineer or line-man desires to throw it to its other position the button M is pressed, throwing current through the magnet G G, attracting the armature O, thus releasing the trigger H; the spring F thereupon carries the handle to its second 70 position.

Having thus described my invention, what I claim, and wish to protect by Letters Patent 75 of the United States, is—

1. In an electric snap switch, the combination of a switch mechanism normally held under tension with a spring F composed of a single piece of wire, coiled at its extremities and 80 having its middle portion engaged by the handle of the switch, substantially as described.

2. In an electric snap switch, a switch mechanism adapted to hold under tension a spring 85 composed of a single piece of wire coiled at its extremities and engaged by its middle portion, in combination with a trigger securing the switch handle and adapted to be operated by a galvanic circuit.

3. In an electric snap switch, switching mechanism normally held under tension, a spring, as F, coiled at its ends, as f f, and having its middle part attached to the handle of the switch, substantially as set forth.

4. In an electric snap switch, a switching mechanism normally held under tension, a spring, as F, having its ends coiled, as f f, and its middle attached to the handle of the switch, in combination with a trigger, as H, engaging 100 a lug, as I, upon the said handle, substantially as described.

5. In an electric snap switch, a switching mechanism normally held under tension, a spring, as F, having its ends coiled, as *ff*, and its middle attached to the handle of the switch, 5 in combination with a trigger, as H, engaging a lug, as I, upon the said handle, the trigger adapted to be operated by a subsidiary galvanic circuit, substantially as set forth.

6. In an electric snap switch, a switching mechanism normally held under tension, a spring, as F, having its ends coiled, as *ff*, and its middle attached to the handle of the switch; 10 in combination with a trigger, as H, engaging

a lug, as I, upon the said handle, the trigger adapted to be operated by a subsidiary galvanic circuit completed by means of a push button, as M: whereby the switch may be operated from a distant point, substantially as described. 15

In witness whereof I have hereunto set my hand this 21st day of January, 1893.

CARYL D. HASKINS.
